Term of patent 14 years

(Cl. D74—1)

FIG. 1.

FIG. 2.

FIG. 3.

FIG. 5.

FIG. 4.

FIG. 6.

FIG. 1 is a front perspective view of a pen clip showing my new design, part of a pen body being shown in broken lines for illustrative purposes;

FIG. 2 is a front elevational view of the pen clip as shown in FIG. 1;

FIG. 3 is a side elevational view thereof, the opposite side being substantially the same in appearance;

FIG. 4 is a top plan view;

FIG. 5 is a transverse section taken plane 5—5 of FIG. 3; and

FIG. 6 is a transverse section taken along plane 6—6 of FIG. 3.

The essential features of the design reside in the portions shown in solid lines on the drawing.

I claim:

The ornamental design for a pen clip or the like, as shown and described.
